CLAIM

The ornamental design for the six-sided chopstick with tip that has rough surface, as shown and described.

DESCRIPTION

FIGS. 1–6 depict one embodiment of this invention where:

FIG. 1 is a perspective view of the six-sided chopstick with tip that has rough surface of this invention looking at the rear end of the chopstick.

FIG. 2 is a perspective view of the six-sided chopstick with tip that has rough surface of this invention looking at the front end of the chopstick.

FIG. 3 is a top view of the six-sided chopstick with tip that has rough surface of this invention.

FIG. 4 is a side view of the six-sided chopstick with tip that has rough surface of this invention.

FIG. 5 is a rear view of the six-sided chopstick with tip that has rough surface of this invention.

FIG. 6 is a front view of the six-sided chopstick with tip that has rough surface of this invention.

FIGS. 7 through 8 depict another embodiment of this invention differing from the first embodiment in length and the rear and front of this embodiment is identical to that shown in FIGS. 5 and 6, respectively, and where:

FIG. 7 is a top view of the six-sided chopstick with tip that has rough surface of this invention; and,

FIG. 8 is a side view of the six-sided chopstick with tip that has rough surface of this invention.
